1

This invention relates to apparatus for determining certain correctional factors involved in the firing of ordnance, more particularly ordnance used against aerial targets.

The invention is particularly intended for use in systems in which guns or the like are controlled from instruments known as directors which transmit to the guns indications of the train and elevation required for properly aiming them. In the case of a gun located at an appreciable distance from the director there is an angular difference between a line from the gun to the target and the line of sight from the director to the target. In practice the gun will be aimed along a line differing in both train and elevation from the line between it and the target to allow for the curvature of the trajectory of the projectiles and the effect of other factors, such as their time of flight, wind, drift and the like, all of which will be ignored as they do not enter into the parallax correction which depends solely upon the distance between the director and the gun, the angular relation between the target and the line joining the director and the gun and the range of the target.

It is accordingly necessary for accurate firing to apply to the indications of train transmitted from the director to the gun a horizontal parallax correction, as it is usually called, to compensate for the error due to the distance between the director and the gun in a horizontal plane. If there be any appreciable distance between the director and the gun in a vertical plane it is also necessary to apply a vertical parallax correction to the indications of gun elevation transmitted from the director to the gun.

Both of these corrections have been applied, either singly or jointly as required, in systems for controlling the firing of ordnance used against surface targets. In the case of aerial targets, however, a further vertical parallax correction is required due to the horizontal distance between the director and the gun as the line representing this distance does not lie in the same plane in which the line from the gun to the target lies, as is the case with surface targets.

It is accordingly an object of this invention to provide apparatus for determining the correction required for the accurate aiming of a gun in elevation from a director by calculating the vertical parallax due to the vertical distance between the director and the gun and the vertical parallax due to the horizontal distance between the director and the gun and correcting the gun elevation in accordance with these two quanti-

2

ties to give the required elevation for accurate pointing of the gun against an aerial target insofar as parallax errors are concerned.

It is a further object of the invention to provide in connection with both horizontal and vertical parallax corrections and for both surface and aerial targets an apparatus for determining such corrections by computing the values of the parallax corrections due to unit base length and 10 converting these values to the required values by multiplying them by the ratio of the actual base length to the unit base length.

One form of apparatus which may be employed for these purposes consists of an instrument for 15 computing the parallax correction due to a unit horizontal base length and converting this value into the required correction by multiplying it by the ratio of the actual horizontal base length to the unit horizontal base length and transmitting 20 to the gun the indications of train corrected in accordance with the required parallax correction.

The invention further comprises mechanism in the instrument for computing the vertical parallax corrections due to both horizontal and vertical 25 unit base lengths and converting these values into the required vertical parallax corrections by multiplying them by the ratios of the actual horizontal and vertical base lengths to the unit horizontal and vertical base lengths. The 30 instrument also combines the vertical parallax corrections due to a horizontal base and to a vertical base and corrects the indications of gun elevation transmitted from the director in accordance with such parallax corrections in order 35 that the gun may be accurately pointed.

The particular nature of the invention as well as other objects and advantages thereof will appear most clearly from a description of a preferred embodiment as shown in the accompanying 40 drawings in which:

Fig. 1 is a diagram used in deriving the equations solved by the apparatus of the invention;

Fig. 2 is a simplified diagram of one form of apparatus in which the invention may be embodied;

Fig. 3 is an enlarged perspective view of the yielding driving mechanism of Fig. 2; and

Fig. 4 is a diagram similar to and showing parts of some of the elements of Fig. 2 but with 50 a different form of operating mechanism.

Referring to Fig. 1, the point D represents an observing station or director located at a unit distance U_V above the plane of reference, usually a horizontal plane, in which a gun is located at 55 the point G lying at a unit distance U_H from a

point A directly below the director D. The point T represents an aerial target, the range R of which from the director is therefore represented by the line D—T. C represents a point in the reference plane below the target, the line T—C being perpendicular to the plane and parallel to the line D—A. The line A—C represents the direction of the point C from the director so that the external angle GAC measured in a clockwise direction represents the bearing of the point C from A referred to the base line U_H , this angle being designated B for convenience in future reference.

The line G—J represents a line from the point G perpendicular to the line A—C and its length is represented by $U_H \sin B$. The portion of the line A—C between A and J is represented by $U_H \cos B$.

J—K is a line from the point J to the line A—T perpendicular to the latter and since in practice the portion K—T of this line is relatively great compared with the portion A—K and differs but slightly from the distance D—T or R, the portion K—T may be assumed to be equal to R.

The line D—M is a line parallel to the line A—C at a distance Uv from the latter. The angle TDM, therefore, represents the elevation of the line of sight from the director D to the target measured relative to the line D—M which is parallel to the reference plane. For convenience this angle TDM will be designated E_v . Since the range of the target is relatively great as compared with the distance Uv the angle TAC may be regarded as approximately equal to E_v .

The length of the line J—K is accordingly represented by $U_H \cos B \sin E_v$. The angle JTK is, therefore, approximately

$$\frac{U_H \cos B \sin E_v}{R}$$

which represents the vertical parallax due to the unit base U_H . For convenience this unit parallax factor will be designated VP_{U_H} .

D—N is a line from the point D perpendicular to the line A—T. The angle DAN is therefore equal to $90^\circ - E_v$ so that the length of the line D—N is $Uv \sin (90^\circ - E_v)$ or $Uv \cos E_v$. The angle DTA is therefore approximately

$$\frac{Uv \cos E_v}{R}$$

which represents the vertical parallax due to the unit base Uv and for convenience this unit parallax factor will be designated VP_{Uv} . The total unit parallax correction in a plane perpendicular to the reference plane, this correction being in the vertical plane when the reference plane is horizontal, will be designated $VP_{U_{HV}}$ and is equal to $VP_{U_H} \pm VP_{Uv}$.

The angle CGT represents the actual elevation of the line from the gun to the target with respect to the reference plane, or in other words, the elevation which must actually be given to the gun to allow for vertical parallax, all other factors being neglected. That is, this angle is equal to the algebraic sum of the angle E_v and the total parallax correction angle $VP_{U_{HV}}$.

Since the portion of the line A—C lying between J and C is relatively great in practice as compared with the portion lying between A and J, it may be assumed equal to $R \cos E_v$ without appreciable error. Since the line G—J is represented by $U_H \sin B$ the angle GCJ is approximately equal to

$$\frac{U_H \sin B}{R \cos E_v}$$

this angle being the unit parallax correction in the plane of reference due to the unit base U_H and for convenience it will be designated HP_{U_H} .

The angle FGC represents the actual bearing of the line from the gun to the target with respect to the base line U_H , or in other words, the bearing which must actually be given to the gun to allow for horizontal parallax. That is, this angle is equal to the algebraic sum of the angle B and the parallax correction angle HP_{U_H} .

In Fig. 2 there is shown in diagrammatic form an instrument for calculating the quantities derived from Fig. 1. It will be understood that all the parts while shown diagrammatically are in practice mounted upon a member 1 rotatably mounted upon a pedestal 2 within an annular rack 3 fixed to the top of the pedestal. Meshing with the rack 3 is a pinion 4 on a shaft 5 suitably mounted upon the member 1 and carrying a gear 6 meshing with a pinion 7 on the lower end of a shaft 8, the upper end of which carries a bevel gear 9 meshing with a corresponding gear 10 on the end of a shaft 11. Meshing with the gear 10 is a bevel gear 12 on the lower end of a shaft 13 which is connected by a pair of bevel gears 14 with a shaft 15 which is connected by bevel gears 16, shaft 17 and bevel gears 18 to a pair of hand wheels 19 adapted to be operated by the trainer of the instrument to follow the movement of a target as viewed by him through a telescope 20 suitably mounted to turn in train with the member 1 and in elevation about an axis represented by a shaft 21 parallel to the member 1. A dial 22 reading against a fixed index 23 to give indications of train or bearing B of the target with respect to the base line U_H of Fig. 1, is mounted at the end of a shaft 24 that is driven from the shaft 15 by a pair of gears 25.

The telescope 20 is moved in elevation by means of a gear 26 on the shaft 21 and meshing with a worm 27 connected by a pair of bevel gears 28 to a shaft 29 which by a pair of bevel gears 30 is connected to a worm 31 meshing with a gear 32 on the shaft 33 of a pointer's telescope 34 which is suitably mounted to move in train with the telescope 20. The shaft 29 extends beyond the bevel gears 30 and is connected by bevel gears 35, shaft 36, and bevel gears 37 to a pair of hand wheels 38 adapted to be operated by the pointer of the instrument who follows the movement of the target in elevation. The elevation angle E_v is indicated by a dial 39 reading against a fixed index 40 and attached to the end of a shaft 41 which is connected by bevel gears 42 to the elevation shaft 29.

Shaft 11 which is rotated in accordance with the bearing angle B by the trainer is connected through bevel gears 43 to a shaft 44 carrying at one end a pinion 45 which meshes with a gear 46 meshing in turn with gear 47 which will, therefore, be turned in accordance with the angle B. Gear 47 is provided with a radial slot 48 within which is mounted a sliding block 49 carrying a rod 50, which extends through a spiral groove 51 in a gear 52 which is rotated in accordance with values of range as will now be described, the spiral groove being arranged to cause a radial movement of the rod 50 in accordance with reciprocal values of range, that is, in accordance with

$$\frac{1}{R}$$

A crank 53 on the end of a shaft 54 is adapted 75 to be turned in accordance with values of range R

2,466,093

5

as received from a suitable instrument, such as a range finder. The values are indicated by a dial 55 reading against a fixed index 56 and mounted upon the end of a shaft 57 connected by bevel gears 58 to the shaft 54. The shaft 54 is also connected by bevel gears 59 to a shaft 60 having its other end connected to the center 61' of a differential 61. One side 61'' of the differential carries a gear 62 meshing with the gear 46, so that this side of the differential receives a movement proportional to the bearing angle B as does the gear 47. The second side 61''' of the differential carries a gear 63 meshing with the

$$\frac{1}{R}$$

gear 52. By virtue of the differential 61 the gears 47 and 52 are turned in accordance with the bearing angle B and the gear 52 receives a displacement relatively to the gear 47 in accordance with range R so that the rod 50 is positioned in accordance with bearing B and reciprocals of range

$$\frac{1}{R}$$

The rod 50 also passes through a slotted arm of a rectangular slide 54 which, therefore, receives a movement proportional to

$$\frac{U_H \cos B}{R}$$

it being understood that the quantity U_H which is a constant representing a unit length of base line is provided for by suitable proportioning of the parts. The rod 50 also passes through a slotted arm of a second rectangular slide 65 which receives a movement proportional to

$$\frac{U_H \sin B}{R}$$

The range shaft 54 is connected at its lower end by bevel gears 66 to a shaft 67, the other end of which is attached to the center 68' of a differential 68. One side 68'' of the differential carries a pinion 69 meshing with a gear 70 provided with a spiral groove 71 like the groove 51 of the gear 52 and designed to cause radial movement of a rod 72 extending through it in accordance with values of

$$\frac{1}{R}$$

The rod 72 is attached to a block 73 slidably mounted in a radial slot 74 in a gear 75 adapted to be rotated in accordance with values of the elevation angle E_v by the following elements. Meshing with the gear 75 is a pinion 76 on the end of a shaft 77 which is connected through bevel gears 78, shaft 79 and bevel gears 80 to the E_v shaft 29. The shaft 77 also carries a gear 81 meshing with a gear 82 attached to the second side 68''' of the differential 68. By virtue of the differential, the gears 70 and 75 are moved in accordance with values of the angle E_v and the gear 70 is displaced relatively to the gear 75 in accordance with values of

$$\frac{1}{R}$$

so that the rod 72 is positioned in accordance with both of these quantities. The rod 72 also extends through a slotted arm of a rectangular slide 83 which is moved in accordance with the quantity

$$\frac{U_v \cos E_v}{R}$$

6

The quantity U_v , which is a constant representing a unit length of base line is provided for in the instrument by suitable proportioning of its parts.

- 5 As shown most clearly in Fig. 3 the vertical arm of the slide 65 is provided with a rack meshing with a pinion 84 loose on a shaft 85 and having a pin 86 normally held against a pin 87 projecting from the shaft by a spring 88 attached at one end of the pinion 84 and at the other end to a collar 89 fastened to the shaft 85. A similar but reversely wound spring 90 is attached at one end to the collar 89 and at the other end to a pinion 91 also loosely mounted on the shaft 85 similarly to pinion 84. The pinion 91 carries a pin 92 normally held by the action of the spring 90 in engagement with a pin 93 attached to the shaft. The pinion 91 meshes with the larger gear of a compound gear 94, the smaller gear of which meshes with a rack on the vertical arm of a rectangular slide 95. The mechanism described in this paragraph constitutes a yielding driving connection between the slide 65 and the slide 95, the operation and purpose of which will be herein-after explained.

- 25 Slidably mounted on the horizontal arm of the slide 95 is a carriage 96 provided with a rod 97 extending through a slot in this arm and into a slotted link 98 restrained at one end by a fixed rod 99 passing through the slot. The other end of the link is attached to a reciprocating rack 100 meshing with a pinion 101 on a shaft 102 connected through bevel gears 103 to a shaft 104 having detachably secured to its lower end a gear 105 meshing with a gear 106 detachably secured to the upper end of a shaft 107.

- It has been previously stated that the instrument computes the value of the horizontal parallax correction for a unit horizontal base length 40 and converts this correction into the required correction by multiplying it by the ratio of the actual horizontal base length to the unit horizontal base length. Since for any particular installation the actual base length is fixed, the gears 105 and 106 45 perform the converting operation, their ratio being suitably selected in accordance with the ratio between actual and unit base lengths. By being detachably secured to their shafts they may be readily changed to adapt them to different installations with different ratios.

- The shaft 107 is connected through bevel gears 108 to the side 109'' of a differential 109, the center 109' of which is attached to a shaft 110 connected by bevel gears 111 to a shaft 112 for actuating a transmitter 113 of any suitable type for sending training indications to the controlled gun. The shaft 112 drives through bevel gears 114, shaft 115 and bevel gears 116, a dial 117 reading against a fixed index 118 to show the 60 values of the indications transmitted to the gun, so that if the transmission system fails indications can be obtained and sent to the gun by other means.

- The other side 109''' of the differential 109 carries a pinion 119 meshing with a gear 120 on the other end of the shaft 44 which as previously explained receives a movement proportional to the bearing angle B from the trainer's hand wheel 19.

- The shaft 29 is connected through bevel gears 121, shaft 122 and bevel gears 123 to the side 124'' of a differential 124. This side also carries a pinion 125 meshing with a gear sector 126, which thus receives from the shaft 29 an angular movement proportional to the elevation angle E_v . The gear sector carries a rod 127 extending

rearwardly into a slotted arm of an inverted U-shaped slide 128 which receives a movement proportional to $\cos E_v$ from the gear sector 126. The other slotted arm of the slide receives the forwardly extending portion of the rod 97. Since as previously described the slide 65 receives a movement proportional to

$$\frac{U_H \sin B}{R}$$

the slide 95 receives through the yielding driving connection consisting of the elements designated 84 to 94, both inclusive, a corresponding movement.

Under normal conditions of operation the spring 88 holds the pins 86 and 87 in engagement so that the movement imparted to the gear 84 by the slide 65 is transmitted through the shaft 85 and the pins 93 and 92 which are held in engagement by the spring 90 as if the shaft constituted a rigid connection between the pinions. Under usual conditions and for consistent values of the movements of the slide 95 representing

$$\frac{U_H \sin B}{R}$$

and slide 128 representing $\cos E_v$, the relation of the slides, pin 97 and link 98 will be such as to cause a movement of rack 100 with no possibility of disengagement of the rack from pinion 101. In practice stops will be provided for limiting the movement of the rack to prevent such disengagement, but when this is done there is a possibility when the instrument is operated for unusual and inconsistent values of the quantities

$$\frac{U_H \sin B}{R}$$

and $\cos E_v$ that the rack 100 will reach one or the other of its stops before the slides have reached positions corresponding to those required by the conditions under which the instrument is being operated.

When this occurs the movement of slide 95 is prevented through the pin 97 and link 98 connected to the rack 100, the movement of which has been stopped. The slide 65 may however continue to move because one or the other of the springs 88 or 90 will be placed under increased tension to permit separation of the pins 86 and 87 or 92 and 93 according to the direction in which the gear 84 is being turned by the slide 65 after movement of the gear 91 has been prevented by the stopping of slide 95 which is connected to the gear by the compound gear 94. The springs 88 and 90 are so designed that while under normal conditions of operation they hold the pins 86 and 87 on the one hand and the pins 92 and 93 on the other hand in engagement, they will yield and permit separation of the pins before there is any danger of damage to any of the elements of the instrument by continued movement of slide 65 after the rack 100 has reached its limits of movement.

As previously explained the slide 95 receives a movement proportional to

$$\frac{U_H \sin B}{R}$$

and the slide 128 receives a movement proportional to $\cos E_v$. These slides are so related as to displace through the rod 97 and link 98 the rack 100 in accordance with the quantity

$$\frac{U_H \sin B}{R \cos E_v}$$

This movement is transmitted to the pinion 101, shaft 102, bevel gears 103 and shaft 104, to the gear 105 which in conjunction with the gear 106 multiplies this quantity by the ratio of the actual base length L_H to the unit base length U_H to give the quantity

$$\frac{L_H U_H \sin B}{U_H R \cos E_v}$$

10 or

$$\frac{L_H \sin B}{R \cos E_v}$$

which is the horizontal parallax correction HP_{L_H}

due to the actual horizontal base length L_H . This quantity is reproduced in the movement of the side 109" of the differential 109 through the shaft 107 and bevel gears 108. Since, as previously explained, the other side 109''' receives a movement proportional to the bearing angle B from the trainer's hand wheels, the center 109' receives a movement proportional to the algebraic sum of the bearing angle and the horizontal parallax correction, that is, $B \pm HP_{L_H}$. The resultant movement of the centre of the differential causes through shaft 110, bevel gears 111 and shaft 112 a corresponding actuation of the transmitter 113 to send to the gun indications of the required train corrected for horizontal parallax. At the same time the measure of this quantity is carried from shaft 112, by bevel gears 114, shaft 115 and bevel gears 116 to the dial 117 where the indication of the quantity is read against its index 118.

It has previously been explained that the slide 83 is moved in accordance with the quantity

$$\frac{U_V \cos E_V}{R}$$

The horizontal arm of this slide is provided with a rack which meshes with a pinion 129 on a shaft 130 connected through bevel gears 131, shaft 132 and bevel gears 133 to a shaft 134 having detachably secured to its upper end a gear 135 meshing with a gear 136 detachably secured to the lower end of a shaft 137. These gears perform the function of converting the quantity

$$\frac{U_V \cos E_V}{R}$$

50 which represents the vertical parallax due to the unit base U_V into the vertical parallax due to the actual base L_V , their ratio being proportional to

$$\frac{L_V}{U_V}$$

In other words, they multiply the quantity

$$\frac{U_V \cos E_V}{R}$$

60 by the ratio

$$\frac{L_V}{U_V}$$

65 giving

$$\frac{L_V \cos E_V}{R}$$

70 which is the required vertical parallax correction VP_{L_V} due to the actual base line L_V . The movement thus imparted to the shaft 137 is proportional to this quantity and is transmitted through bevel gears 138 and shaft 139 to the center 140" of a differential 140 which is attached to the other end of the shaft.

75 The rod 127 carried by the E_V gear sector 126

extends forwardly into the slotted arm of a U-shaped slide 141 the other slotted arm of which receives the rear end of a rod 142 projecting from a carriage 143 slidably mounted on the vertical arm of a rectangular slide 144, the arm being slotted to permit the passage through it of the rod. The horizontal arm of this slide is provided with a rack meshing with a pinion 145 on a shaft 146 to which is detachably secured a gear 147 meshing with a gear 148 detachably secured to the side 140'' of the differential 140. As previously explained slide 64 receives a movement proportional to

$$\frac{U_H \cos B}{R}$$

The end of this slide is connected by a slotted link 149 to the rod 142 which extends through the slot. The other end of the link is restrained by a fixed rod 150. The slide 141 receives a movement proportional to $\sin E_v$. The slide 144 therefore, receives a movement proportional to the product of these quantities, that is, proportional to

$$\frac{U_H \cos B \sin E_v}{R}$$

which is the vertical parallax correction VPU_H due to the unit horizontal base line U_H . The gears 147 and 148 have a ratio proportional to

$$\frac{L_H}{U_H}$$

the same as the gears 105 and 106 and they multiply the quantity

$$\frac{U_H \cos B \sin E_v}{R}$$

by

$$\frac{L_H}{U_H}$$

giving

$$\frac{L_H \cos B \sin E_v}{R}$$

which is the vertical parallax correction VPL_H due to the actual horizontal base L_H .

Since the centre 140'' of the differential 140 receives a movement proportional to the vertical parallax correction due to the actual vertical base L_v and the side 140'' receives a movement proportional to the vertical parallax correction due to the actual horizontal base L_H , the other side 140' receives a movement proportional to the algebraic sum of these corrections, that is, $VPL_v \pm VPL_H$ or VPL_{HV} the total vertical parallax correction. This side is rigidly connected to the side 124''' of differential 124 of which the center 124' is connected to a shaft 151, which thus receives a movement proportional to the elevation angle E_v through the side 124'' and the total vertical parallax correction VPL_{HV} through side 124''' of the differential, the movement of the shaft thus representing the elevation indication which should be transmitted to the gun as corrected for vertical parallax, or $E_v \pm VPL_{HV}$. This is accomplished by a drive from the shaft 151 through bevel gears 152, shaft 153, bevel gears 154, shaft 155, bevel gears 156, shaft 157, bevel gears 158 and shaft 159 of a transmitter 160 connected to a suitable receiver at the gun. The shaft 155 also drives through bevel gears 161 and shaft 162, a dial 163 reading against a fixed index 164 to give indications of the corrected elevation being transmitted to the guns for use

in case the transmission system fails and it is necessary to convey the information by other means.

In Fig. 4 is shown a modified form of operating connection between the slides 65 and 95 and the rack 100. In this arrangement, the slide 65 of Fig. 2 drives through pinion 84, shaft 166, and pinion 167 a pinion 168 on the side 169'' of a differential 169. The other side 169''' of the differential carries a pinion 170 meshing with a pinion 171 on a shaft 172 which is connected through a pair of pinions 173, shaft 174 and pinion 175 with a gear 176 having integral therewith the compound gear and pinion 94 meshing with the rack of the slide 95.

The center 169' of the differential is attached to a shaft 178 which carries a cam 179 having substantially semi-circular portions of unequal radii. The cam operates a contact device 180 of the general type shown in more detail in my Patent No. 1,577,618, granted March 23, 1926, for Speed regulating mechanism. In the normal condition of the device, its roller 181 engages an intermediate cam portion between the dwells 25 of the cam 179 and the contact arm 182 of the device lies midway between fixed contacts 183 and 184. The contact arm has a portion insulated from the rest of the device and electrically connected by a conductor 185 to the positive main 20 186 of a source of supply. The contacts 183 and 184 are connected by a conductors 187 and 188 respectively to the reversely wound field windings of a motor 189 of any suitable type and the circuit is completed through its armature 30 35 and then by a conductor 190 leading to the negative main 191. The motor drives through shaft 192 and pinion 101 the rack 100 corresponding to the similarly designated rack of Fig. 2. The shaft 192 also drives through bevel gears 194 40 shaft 104 of Fig. 2.

In the operation of this modification of the invention the movement of slide 65 is transmitted through pinion 84, shaft 166 and pinions 167 and 168 to the side 169'' of differential 169. 45 Regarding its other side 169''' as fixed since it is connected to the slide 95, the center 169' will be turned to turn the cam 179 by shaft 178. This will actuate the contact device 180 to shift its arm 182 into engagement with one or the 50 other of the contacts 183 or 184 according to whether the roller 181 moves outwardly or inwardly as a result of the turning of the cam. A circuit is, therefore, established from the main 186 through conductor 185, arm 182, one or the 55 other of the contacts 183 or 184 and the conductor 187 or 188 connected thereto, the corresponding field winding of the motor 189, the armature of the motor and conductor 190 leading to the other main 191. Through shaft 192 60 and pinion 101 the motor moves the rack 100 to position the link 98 and rod 97 that are shown in Fig. 2. The movement imparted to the rod displaces the slide 95 and through the compounded pinion and gear 94, pinion 175, shaft 65 70 174, pinions 173, shaft 172, pinions 171 and 170, the side 169''' of the differential will be displaced. Regarding the other side 169'' as now fixed, the center 169' will be displaced, but in the opposite direction to its former displacement to oppositely 75 turn the cam 179 to restore the contact device 180 to its normal position and open the circuit of the motor 189.

The elements above described constitute a follow-up system by which the movement of slide 75 65 is reproduced at slide 95 and the corresponding

movement of the rack 100 is also produced, as in the case of these same elements described in connection with Fig. 2. If under unusual and inconsistent values of the quantities involved the rack 100 reaches one of its stops before the slide 65 reaches its required position the motor will be stopped, but the cam 179 will continue to turn without offering any appreciable resistance to the movement of the slide 65, so that there is no danger of damage to any of the elements of the instrument. In other words, the modification shown in Fig. 4 performs the function of the yielding driving connection of Figs. 2 and 3 but has the advantage over such a mechanical drive in that additional power from the motor is obtained for operating the elements of the instrument. When the slide 65 again reaches a position corresponding to consistent values of the quantities involved the motor will again become effective to actuate the rack 100 as above described.

While the invention has been described in connection with an aerial target it is equally adapted for controlling ordnance used against surface targets. In this case the angle E_V is zero and there is no vertical parallax due to the base U_H , but only that due to the base U_V and the horizontal parallax due to the base U_H . In other words, the expression

$$\frac{U_H \cos B \sin E_V}{R}$$

representing the vertical parallax due to the base U_H becomes zero. In other respects the invention is the same and the instrument operates as described in connection with an aerial target.

While certain preferred embodiments of the invention have been described, it will be understood that it may be embodied in other forms and that various changes in structural details may be made without departing from the principle of the invention as defined in the appended claims.

I claim:

1. In an instrument for determining an angular correctional factor depending on a plurality of variables, the combination of means for computing the value of the factor for unit value of one of the variables and means for multiplying the value of the factor by the ratio between the actual value of the variable and the unit value thereof said second mentioned means being detachably associated with said first mentioned means to allow for altering of the multiplying ratio when the ratio between the actual value of the variable and unit value thereof is altered.

2. In an instrument for determining a parallax correction the combination of means for computing the value of the correction for a unit base length and means for multiplying the value of the correction by the ratio between the actual base length and the unit base length, said multiplying means being detachably associated with said computing means to provide for altering the multiplying ratio to conform with the ratio between the actual base length and unit base length.

3. In an instrument for computing the vertical parallax correction for ordnance used against aerial targets, the combination of means for computing the vertical parallax correction due to a vertical base, means for computing the vertical parallax correction due to a horizontal base and means actuated by said first and second means for combining the computed corrections to give the total correction.

4. In an instrument for determining the angu-

lar relation of an object with respect to a base line lying in a reference plane and between two separated points from one of which the angular relation is known, the combination of means for

5. determining the angular relation corresponding to a unit length of the base line between the points including an element displaceable in accordance with a function of the known angular relation of the object, a second element displaceable in accordance with a function of the distance of the object from the point from which the angular relation is known, means for combining the displacements of the members, a third element displaceable in accordance with a function of the angular relation of the object with respect to the reference plane, and means for combining the movements of the first combining means and the third element, means for multiplying the movement of the second combining means by the ratio of the actual length of the line between the points to a unit length of said line and means for correcting the known angular relation of the object in accordance with the correctional alteration of the angular relation as determined by the last named means.

6. In an instrument for determining a parallax correction, the combination of means for determining the parallax correction due to a unit length of the base line between two points including an element displaceable in accordance with a function of the bearing of a distant object from one of the points, a second element displaceable in accordance with a function of the range of the object, means for combining the displacements of the members, a third element displaceable in accordance with a function of the angle of elevation of the object and means for combining the movements of the first combining means and the third element and means for multiplying the movement of the second combining means by the ratio between the actual length of the base line and the unit length thereof.

7. In an instrument for determining a parallax correction, the combination of means for determining the parallax correction due to a unit length of the base line between two points including an element displaceable in accordance with a function of the elevation of a distant object, a second element displaceable in accordance with a function of the range of the object and means for combining these displacements of the members, and means for multiplying the movement of the combining means by the ratio between the actual length of the base line and the unit length thereof.

8. In an instrument for determining the bearing of an object from one of two separated points from the other of which the bearing is known, the combination of means for determining the parallax corrections due to a unit length of the base line between the points including an element displaceable in accordance with a function of the bearing of the object, a second element displaceable in accordance with a function of the range of the object, means for combining the displacements of the members, a third element displaceable in accordance with a function of the angle of elevation of the object and means for combining the movements of the first combining means and the third element, means for multiplying the movement of the second combining means by the ratio between the actual length of the base line and the unit length thereof and means for correcting the bearing of the object from one of the points by the determined

2,466,093

13

parallax correction for the actual base length to give the bearing of the object from the other point.

8. In an instrument for determining a parallax correction, the combination of means for determining the parallax correction due to a unit length of the base line between two points including an element displaceable in accordance with a function of the elevation of a distant object, a second element displaceable in accordance with a function of the range of the object and means for combining the displacements of the members, and means for multiplying the movement of the combining means by the ratio between the actual length of the base line, and the unit base length, means for determining a second parallax correction due to a unit length of a second base line between one of said two points and a third point including an element displaceable in accordance with a function of the bearing of the object, a second element displaceable in accordance with the range of the object, means for combining the displacements of the members, a part displaceable in accordance with a function of the angle of elevation of the object and means for combining the movements of the second combining means and the part, means for multiplying the movement of the third combining means by the ratio between the actual length of the second base line and the unit length thereof, and means for combining the movements of the two means for determining parallax corrections to give the total parallax corrections.

9. In an instrument for determining the angular relation of an object with respect to a base line lying in a reference plane and between two separated points from one of which the angular relation is known, the combination of means for determining the angular relation corresponding to a unit length of the base line between the points including an element displaceable in accordance with a function of the known angular relation of the object, a second element displaceable in accordance with a function of the distance of the object from the point from which the angular relation is known, means for combining the displacements of the members, a third element adapted to be displaced in accordance with the combined displacements of the elements, a yielding driving connection between the combining means and the third element, a fourth element displaceable in accordance with a function of the angular relation of the object with respect to the reference plane, and means for combining the movements of the third and fourth elements, means for multiplying the movement of the second combining means by the ratio of the actual length of the base line between the points to the unit length of said line and means for correcting the known angular relation of the object in accordance with the correctional alteration of the angular relation as determined by the last named means.

10. In apparatus for transmitting the movement of one member to another member, the combination of an element operatively connected to the first member, a part movably related to

14

the element, means connected between the element and the part for normally holding them in fixed relation but adapted to yield to permit relative movement between them, a second element operatively connected to the second member and movably related to the part and means connected between the second element and the part for normally holding them in fixed relation but adapted to yield to permit relative movement between them.

11. In apparatus for transmitting the movements of one member to another member, the combination of a gear operatively connected to the first member, a shaft upon which the gear is movably mounted, resilient means connected between the gear and the shaft for normally holding them in fixed relation but adapted to yield to permit relative movement between them, a second gear operatively connected to the second member and movably mounted upon the shaft and resilient means connected between the second gear and the shaft for normally holding them in fixed relation but adapted to yield to permit relative movement between them.

12. In an instrument for determining training and elevational movements for a gun used against an aerial target including horizontal and vertical parallax corrections, the combination of means operable in accordance with required uncorrected movements of the gun in elevation and train, means for computing vertical parallax corrections due to vertical and horizontal unit bases, means for computing a horizontal parallax correction due to the horizontal unit base, mechanisms for multiplying the respective computed corrections by the ratios between the unit bases and the actual vertical and horizontal bases, and means for combining the vertical and horizontal parallax corrections with the required elevational and training movements effected by the first named means.

HANNIBAL C. FORD.
